UNITED STATES PATENT OFFICE.

ROY F. DOWDY, OF ROANOKE, VIRGINIA, ASSIGNOR TO SAFETY GAS LIGHTER CORPORATION, OF ROANOKE, VIRGINIA, A CORPORATION OF VIRGINIA.

ELECTRIC GAS-LIGHTER.

1,295,285.

Specification of Letters Patent.

Patented Feb. 25, 1919.

Application filed March 23, 1918. Serial No. 224,259.

To all whom it may concern:

Be it known that I, ROY F. DOWDY, a citizen of the United States, residing at Roanoke, in the county of Roanoke and State of Virginia, have invented certain new and useful Improvements in Electric Gas-Lighters, of which the following is a specification.

This invention relates to electric gas lighters and the general object thereof is to provide improvements in devices for igniting gas at gas burners or the like by means of a spark derived from an ordinary house-lighting circuit. With this general and other specific objects in view the invention consists of the formation, combination and arrangement of parts as will be herein described and particularly claimed.

In the accompanying drawings Figure 1 is a view showing the associated parts of the device in their connected relationship. In this figure the parts are shown in longitudinal section and also the ordinary wiring and the gas stove or burner is omitted. Fig. 2 is a transverse section taken through the resistance unit on the line 2-2 of Fig. 1. Fig. 3 is a similar view taken through the lighting point on the line 3-3 of Fig. 1. Fig. 4 is a general view of the installed apparatus showing the relationship of the gas burner and also showing in diagram the electric wires.

In these drawings there is shown the customary wires 10 and 11 of an alternating electric circuit and in this circuit is connected in the usual manner a commercial socket or receptacle 13, which in the present embodiment is of the standard Edison base type. The wires 14 and 15 connect this receptacle in the circuit. The one side 10 of the circuit is grounded as indicated at 16 and in the connection of the lighting device the grounded contact of the receptacle is blanked off or insulated in a manner to be later described as the ungrounded side only is used from the receptacle on.

A gas stove 17 is shown, this having a burner 18. A metallic gas supply pipe 19 must be suitably connected to or embedded in the ground which is indicated at 20.

Attached to the receptacle by screwing it into the Edison base is a relatively fixed resistance unit 21 and a single wire 22 connects this with a movable lighting point 23, the latter having an electrode 24 which is located adjacent the gas burner and is adapted to be

brought into momentary contact with the metallic burner. Thus making and breaking the circuit through the ungrounded side of the circuit and the metallic gas pipe ground the gas may be ignited in a safe and convenient manner.

The resistance unit is located remote from the lighting point both to save it from mechanical strains and to protect the lighting point from the heat from the resistance. Also the life of the parts is increased and the construction simplified. At 25 is shown how more than one lighting point may be supplied from a single resistance unit.

The resistance unit is constructed of a tubular body or casing 26 which is made of wood, rubber or other insulating material and the upper end of this tube is exteriorly threaded at 27 to coöperate with the threads of the Edison base, thus in a simple manner insulating the wire 14 and the connected terminal of the receptacle, the wire 15 being connected to the other terminal of the receptacle. A U-shaped leaf spring 41 is secured within the cavity of the body and at the upper end thereof by means of the bolt 28. This bolt extends axially of the tubular body through the upper end or integral head of the same and the exposed bolt head 29 forms a contactor for the central terminal of the receptacle.

The resistance element 30 is made up of a suitable length of flat resistance wire 31 which is wound in a helical path upon a core 32 of molded asbestos, the turns of the wire being properly spaced from each other. The core is of less diameter than the cavity of the casing 26 and is also provided with an inner head 33 and an outer head 34, these being made of an insulating material such as hard fiber and being of such dimensions as to fit snugly within the cavity of the casing 26. A bolt 35 passes axially through both of these heads and through the core and is used to clamp these parts together. The head of the bolt is let into the outer face of the head 34 and the point of the bolt is arranged to contact the free end of the leaf spring 41.

The casing 26 is formed with a detachable head 36 at its lower end, this being screwed to the main portion of the casing. Overlying the insulating head 34 is an insulating shield 37 which is attached to the head 34 by means of the two bolts 38, these being iso-

lated from the central bolt 35. This shield insulates the head of the bolt 35 and its edges are clamped between the body of the casing 26 and the head 36.

5 Current passes through the bolt 28 and the leaf spring 41 to the bolt 35. The upper terminal of the resistance wire 31 is secured beneath the nut on the bolt 35 and hence the current passes thence through the resistance 10 wire to the one bolt 38. A metallic connector 39 extends between the bolts 38 and carries the current to the wire 22, the upper end of which is secured beneath the nut of the other of these bolts 38. The wire 22 is 15 knotted within the cavity of the head 36 so that the connections are relieved from mechanical strains.

The lighting point 23 is likewise made up of a hollow body 42 of insulating material with a detachable upper head 43 screwed to it and through which the wire 22 passes, the wire being similarly knotted at 44 within the cavity of the head. Clamped between the head 43 and the body is an insulating washer 25 45 and to the lower or inner face thereof is secured by means of bolts 46 a longitudinally extending, metallic leaf spring 47. The lower terminal of the wire 22 is secured beneath the nut on one of the bolts 46.

30 The wall of the body 42 is pierced to admit a push button 48, through a channel in the inner portion of which the leaf spring 47 is passed. The leaf spring thus retains the push button and the latter in turn prevents 35 the rotation of the leaf spring and the washer 45 within the body. Extending through the lower integral head of the body 42 is the electrode 24 which has a surrounding shield 49. Both the inner end and the 40 outer point of the electrode, however, are exposed, the latter for contacting the metal of the gas burner and the former for contacting the free end of the leaf spring 47 when the push button 48 is depressed.

45 Current will thus, when the circuit is closed by depressing the push button, pass through the wire 22, one of the bolts 46, and

the leaf spring 47 to the electrode. By now drawing the electrode over the gas burner an igniting spark may be safely obtained.

50 Thus has been described a preferred embodiment of the present invention. Other embodiments are possible within the scope of the appended claims without departing from the spirit thereof.

55 What is claimed is:

1. In an electric gas lighter an alternating electric circuit having one side thereof grounded, a gas burner having a metallic connection with the ground, a commercial receptacle wired in the said circuit in the usual manner, a hollow member formed of an insulating material and adapted to be attached to the receptacle, a resistance unit within the hollow member arranged to be connected to the ungrounded side of the circuit when the said member is attached to the receptacle, the attachment being such as to insulate the grounded side of the circuit at the receptacle, a lighting point adjacent the burner and adapted to be brought into momentary contact therewith, and a connection between the resistance unit and the lighting point.

2. In an electric gas lighting device an electric circuit having one side thereof grounded, a screw-base receptacle wired therein, a tubular member formed of an insulating material and having threads on one end thereof to coöperate with those of the receptacle, a resistance unit within the receptacle, an electric connection extending therefrom through the screw-end of the tubular member and adapted to contact the central electric terminal within the receptacle, means at the other end of the tubular member for entering and for restraining the resistance unit, a gas burner having a metallic connection with the ground, a lighting point adjacent the burner, and a connection between the resistance unit and the lighting point.
